UNITED STATES PATENT OFFICE.

FREDERICK E. DAYES, OF BROOKLYN, NEW YORK.

INTERNAL-COMBUSTION ENGINE.

962,131.

Specification of Letters Patent. Patented June 21, 1910.

Application filed May 28, 1909. Serial No. 493,983.

To all whom it may concern:

Be it known that I, FREDERICK E. DAYES, a citizen of the United States, residing at Brooklyn, in the county of Kings and State 5 of New York, have invented new and useful Improvements in Internal-Combustion Engines, of which the following is a specification.

This invention relates to improvements in 10 internal combustion engines and more particularly to a means for automatically advancing or retarding the spark.

It is the object of this invention to provide a means operated by the driving shaft 15 of the engine by which the spark will automatically be advanced or retarded in accordance with the load upon the engine so that the spark in each cylinder will always occur at the proper moment when each piston 20 ton is in the position whereby the maximum efficiency of the engine will be obtained.

Heretofore devices of this character have been constructed in which a piston adapted to impart movement to a member to be adjusted, is subjected to the pressure of a body 25 of fluid supplied from a pump, which is in turn actuated by the engine to be controlled. Such devices, however, are unsatisfactory when applied to the ignition device of an 30 internal combustion engine because the adjusting movement commences with the initial operation of the engine and bears a constant relation to the speed of the engine.

The object of the present invention is to 35 provide a fluid pressure means in which the pressure only varies as the speed of the engine changes but the effect of the fluid pressure is first neutralized until the initial speed of the engine develops, then commences to act, but progressively decreases as 40 the speed of the engine increases so that the movement of the timer is *nil* at first, then relatively large during the first part of the acceleration of the engine but is relatively 45 slight during the latter part of the acceleration, thus obtaining automatically the same conditions that are established by direct manual control of a timer when properly manipulated. In carrying out the 50 invention, means are combined with the timer whereby pressure of the fluid in the pressure chamber is initially relieved to a degree that will prevent any effect upon the adjusting device while the engine is working up to a predetermined speed, and means

whereby the pressure is thereafter additionally relieved in progressively increasing proportion, so that the movement imparted to the piston, while continuing as long as there is an increase in speed, up to a 60 desired limit, is constantly less in proportion to the increase of speed as the adjustment continues.

While the preferred form of this invention is illustrated in the accompanying sheet 65 of drawing, yet it is to be understood that minor detail changes may be made without departing from the scope thereof.

Figure 1 is a side elevation of an engine showing the application of this device. 70 Fig. 2 is an enlarged detail view in section through the air compressor and operating mechanism. Fig. 3 is an enlarged view in section with parts broken away taken through the operating mechanism. 75

A rotary air compressor 1 of any desired form is secured to the casing 2 of the engine and is geared to the driving shaft 3. In this instance a rotary fan 4 is inclosed in a casing and the driving shaft of the fan is 80 geared through a pinion to the driving shaft of the engine. An inclosed cylindrical casing 5 is secured to the engine casing in proximity to the air compressor and one end of the cylindrical casing is in communication with the air compressor. A piston 6 is mounted within the casing having a piston rod 7 extending through a sleeve 14 in the other end of the casing. The piston rod 7 is secured by a link connection 8 to the timer 90 or spark controlling mechanism 9. The piston 6 is mounted to slide back and forth within a portion of the casing, the remainder of the casing being somewhat smaller in diameter forms a shoulder 10 which limits 95 the movement of the piston. A coil compression spring 11 is mounted upon the piston rod between the piston head and the sleeve 14 in the end of the casing through which the piston passes. The portion of the 100 cylindrical casing within which the piston travels is provided with a series of apertures 12 through which the air may pass. An escape valve 13 is provided in the shouldered portion of the cylinder which may be regulated to allow air to escape therethrough until the compression has reached the predetermined point. The sleeve 14 through which the piston rod 7 passes is externally 105 screw threaded to engage the end of the cas- 110

ing. The tension on the spring 11 may be regulated by advancing or withdrawing the sleeve 14.

The operation is as follows: When the engine is started the fan 4 will begin to revolve causing the air in the casing 5 to be compressed. The escape valve 13 in the casing 5 is adjusted to allow the air therein to escape until the compression has reached a certain degree. As the speed of the driving shaft increases the pressure upon the confined air will increase to such a degree that the pressure will not be completely relieved by the escape valve. This extra pressure will force the piston backward upon the coil spring 11 successively exposing the discharge apertures 12 in the side of the casing until the pressure within the casing balances the pressure of the spring. This movement will be imparted by the piston rod 7 to the timer or spark controlling device 9 which will advance the spark corresponding to the revolutions of the shaft. As the load upon the engine increases the revolutions of the driving shaft will become less and therefore the compression within the casing will be decreased, allowing the piston to advance and retard the spark through the timer or spark controlling device.

It will be readily seen that by this construction the explosion will be caused to occur in each cylinder at the proper moment to obtain the maximum efficiency of the engine, and the device will positively operate under all conditions under which the engine can be operated.

As the number of apertures permitting the escape of air is constantly added to, during the movement of the piston in the direction of advancing the timer, it follows that, the amplitude of the piston's movement is not directly proportional to the increase of the speed of the engine but is continually lessened so that as the highest speed is reached and the point of ignition gets closer to the neutral point of the crank, the movement of the timer will be materially lessened.

What I claim is:—

1. An automatic adjusting means for timers of internal combustion engines, comprising a fluid pressure driven member having positive connections through which it is adapted to effect the adjustment, a fluid pressure developing member actuated by and proportionally to the speed of the engine to be timed, supplying pressure medium to said

driven member, and means for wholly relieving the pressure supplied to said driven member, during the initial speed and progressively enlarging such pressure relief as 60 the adjustment develops.

2. In combination with the timer of an internal combustion engine, an adjusting means for determining the adjustment thereof, comprising a fluid pressure driven member having direct connections through which it is adapted to effect the adjustment, a fluid pressure developing member supplying pressure medium to said driven member, and means for relieving the pressure supplied 70 to said driven member, initially relieving the pressure sufficient to prevent adjustment and thereafter progressively enlarged by said driven member, as adjustment develops, and gradually reducing the amplitude of adjustment.

3. An adjusting means for timing an internal combustion engine, comprising a fluid pressure driven member adapted to effect the adjustment, a fluid pressure developing member supplying pressure medium to said driven member, an initial pressure-medium relief preventing actuation of the fluid pressure driven member until after a predetermined engine speed is developed, 85 and an additional means for relieving the pressure supplied to said driven member, progressively enlarging as the adjustment develops.

4. A device for adjusting the timer of an internal combustion engine, comprising a pressure chamber for fluid pressure, a piston adapted to be moved by fluid pressure in said chamber and a fluid pressure developing means adapted to be actuated by the engine to be controlled, supplying the fluid medium under pressure to said chamber; said chamber being provided with a constantly open but restricted initial escape opening for the pressure medium, means resisting movement of the piston under pressures that are within the relieving capacity of said initial escape opening, but yielding under pressures in excess thereof and progressively enlarging escape passage for the pressure fluid, gradually uncovered by the movement of the piston.

FREDERICK E. DAYES.
